FLUID OPERATED PRESS AND CONTROL
THEREFOR

George Couri, Astoria, N. Y.

Application August 29, 1946, Serial No. 693,763

1 Claim. (Cl. 121—46.5)

2

1 My invention relates to an improvement in air presses, for example laundry air presses, and has for one of its objects to provide electric controls and a master air valve for air presses, whereby the construction and operation of such machines are greatly simplified.

A further object of my invention is to provide an air press, such as a laundry air press for example, wherein the press is more efficient to operate and maintain as compared with conventional machines, and quicker in opening and closing and safer and more economical to operate.

In the accompanying drawing,

Fig. 1 is a sectional elevational view of a master air valve embodying my invention; and

Fig. 2 is a wiring diagram of the controls therefor.

Referring to the drawings in detail, 2 designates the body of the master air valve. This body is provided with air supply port 4, always connected to air feed line 6, supplied with air under pressure from any suitable source.

The air supply port or air intake port 4 opens into a chamber 8, which is formed in the upper part of the valve body. For clarity of description this chamber will be referred to as an air pressure chamber.

The valve body is provided also with another chamber, designated 10, and which will be referred to as air exhaust chamber, this chamber being provided with exhaust port 12, to which is attached exhaust manifold 14.

The chambers 8 and 10 are separated by a partition or wall 16, which is bored axially, as shown at 18, for the reception of rod 20 which is a loose fit in the bore 18.

The partition or wall 16 is further provided with a port 22, to which is connected hose line or pipe 24, permanently connected to the cylinder 26 for air-operated piston 28. This air-operated piston may be the air piston of a laundry machine for example, but it is to be understood of course, that this invention is not to be limited to laundry machines.

The rod 20 above referred to carries exhaust valve 30 for controlling port 32 at the lower side of wall or partition 16, and a stop disc 34. The rod terminates at its inner end within the air pressure chamber 8, while its other end projects through sealing cap 36, which is screwed into the lower end of the valve body 2. The sealing cap also provides a bearing for the rod 20.

Loosely mounted upon the upper end of the rod 20 is spring-loaded air-supply valve 38, controlling port 40. The spring for this valve is 55 designated 42, and it is mounted upon the valve

stem 44. This stem extends upwardly into sealing cap 46, screwed into the upper end of the valve body 2.

It will be apparent from all of the foregoing 5 that, to actuate the piston 28 of the air press, it is merely necessary to raise the rod 20 sufficiently to close exhaust valve 30 and open air-supply valve 38. Air under pressure can then flow from the supply line 6, port 40, bore 18, port 22, line 10 24 to cylinder 26 beneath the piston. Upon movement of the rod 20 in the opposite direction, valve 38 will close under action of its spring 42, valve 30 will open, and cylinder 26 will then 15 exhaust by way of port 22, bore 18, ports 32 and 12.

Actuation of rod 20 and hence of the valves 30 and 38 is effected electrically in accordance with my invention.

Referring now to the wiring diagram of Fig. 2 20 as well as to the apparatus illustrated in Fig. 1:

As hereinbefore pointed out, the rod 20, to which valve 30 is secured, and which rod also unseats air-supply valve 38, projects through the lower end of the valve body 2. The projecting 25 end of this rod, which I shall designate 48, is adapted to be engaged by an actuating arm 50. This arm is pivotally attached at one end to a pin 52, mounted in a fixed block 54. Adjacent the opposite end of the arm I provide an adjustable stop 56 for adjusting the throw of the arm in a direction to limit movement of rod 20 outwardly of the valve body. This end of the actuating arm 50, the outer end, carries the core 58 of a solenoid, the winding for which is designated 60. The fulcrum for the inner end of arm 50 is 30 unstable which can be depressed in block 54 against the tension of its spring. This eliminates the precise setting of the valves and the throw of solenoid core 58, the unstable fulcrum of arm 50 permitting of slight movement of the solenoid core after the exhaust valve strikes its seat, to ensure full seating of the valve as well as full stroke of the solenoid plunger.

62 and 64 designate a pair of push button 45 switches, which must be closed to initiate operation of the press. 66 designates another push button switch, which for clarity will be referred to as a release switch.

69 is a switch one element of which is attached 50 to the press in such position that, the operator's hands must be upon the switches 62 and 64 when the press is closing, and closure of the press can not be continued upon removal of the operator's hands from 62 and 64 unless the press has closed 55 sufficiently to close switch 69.

70 designates a holding relay.

In operation, and assuming that the parts are all in the position shown on the drawings:

The operator closes push button switches 62 and 64 (release switch 66 is initially closed). A circuit is now closed for the solenoid winding 60, which may be traced as follows: From one side of the line, conductor 68, release switch 66, control switches 64 and 62, conductors 72, 74, 78, solenoid winding 60, and conductor 76 to the other side of the line. At the same time, a circuit is closed to the coil of holding relay 70. This circuit may be traced from conductor 74, one contact 80 of the relay, then through the coil and by way of conductor 82 to conductor 76.

The solenoid winding 60 now being energized, its core 58 will be actuated to raise the arm 50, thereby to actuate rod 29 to close the exhaust valve 30 and open air-supply valve 38. Air under pressure, therefore, may now flow to the cylinder 26 beneath piston 28 to actuate or raise the same to close the press. When the press is nearly closed, the switch 69, the movable contact of which is carried by the press, will close. With the holding relay 70 and safety switch 69 closed, the buttons 62 and 64 may be released, and the press will remain closed. At this instant, the circuit for the solenoid winding 60 may be traced as follows: From one side of the line, conductor 68, release switch 66, conductor 84, switch 69, holding relay contacts, conductor 78, solenoid winding 60, conductor 76 to the other side of the line. The holding relay circuit at this time may be traced as follows: Conductor 84, holding relay coil, conductors 82 and 76.

A condition now exists where the starting switches 62 and 64 are opened, but release switch 66 and safety switch 69 are closed, so that the circuits to the holding relay and winding 60 of the solenoid are closed, and the press will remain closed as long as desired.

To open the press, it is merely necessary to open switch 66 momentarily, which will open the circuits of the holding relay and the solenoid, so that lifting arm 50 will be pivoted by its spring to its initial position, allowing rod 29 to move outwardly of the valve body 2. This will close the air-supply valve 38 and open the exhaust valve 30, so that the pressure in cylinder 26 will be lowered, permitting the piston 28 to be restored to the position shown in the drawings, to open the press.

It will be understood that, upon release of

switch 66, it will immediately close, so that upon subsequent operation of the press the same cycle of operations is gone through as above described.

It will be seen from all of the foregoing that my construction is extremely simple and yet reliable in operation. That no effort is required of the operator other than operation of the two push button switches 62 and 64 to close the press and of push button switch 66 to open the press.

It will be appreciated also that the number of valves, air lines, etc. has been reduced to a minimum.

It is to be understood that the details of construction and arrangement of parts hereinabove described and illustrated in the drawings may be varied within the purview of my invention.

What I claim is:

In a fluid operated press, the combination of a supply valve and an exhaust valve for controlling the application of power to the press, a solenoid having a core for controlling the operation of said valves, a rod carrying said valves, an arm engaging said rod and having one end attached to the core of said solenoid, its other end being pivoted, whereby energization of said solenoid will effect movement of said rod and valves to seat the exhaust valve and open the supply valve, the pivot for the arm comprising a fixed member, a pin passing loosely therethrough and pivotally attached to the end of the arm and a spring on said pin between the fixed member and the end of the arm, thereby to permit the pivoted end of the arm to yield upon seating of the exhaust valve and the solenoid core to complete its stroke.

GEORGE COURI.
